CLAIM

The ornamental design for a respiratory system conduit with connector as shown and described.

DESCRIPTION

FIG. 1 is a front perspective view of a respiratory system conduit with connector embodying our design;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

The respiratory system conduit with connector is shown with symbolic break lines. The break lines and appearance of any portion of the article between the break lines form no part of the claimed design.

The broken lines in the drawings illustrate portions of the respiratory system conduit with connector which form no part of the claimed design.
